UNITED STATES PATENT OFFICE.

ERNEST B. NELSON AND JAMES T. FINDLAY, OF ABILENE, KANSAS.

DESIGN FOR A DISPLAY CASE.

Application filed June 3, 1926. Serial No. 17,930. Term of patent 14 years.

To all whom it may concern:

Be it known that we, ERNEST B. NELSON and JAMES T. FINDLAY, citizens of the United States, residing at Abilene, in the county of Dickinson and State of Kansas, have invented a new, original, and ornamental Design for Display Cases, of which the following is a specification, reference being had to the accompanying drawing, forming part thereof.

Figures 1 and 2 are front and rear perspective views, respectively, of a display case, showing our new design.

We claim:

The ornamental design for a display case, as shown.

ERNEST B. NELSON.
JAMES T. FINDLAY.
